UNITED STATES PATENT OFFICE.

JOSEPH A. BEASLEY, OF TAMPA, FLORIDA, ASSIGNOR TO MARTHA ANDERSON
BEASLEY, OF TAMPA, FLORIDA.

BUILDING CONSTRUCTION.

Application filed September 19, 1927. Serial No. 220,514.

This invention relates to building units, the general object of the invention being to provide means whereby a structure can be easily and quickly erected by unskilled labor, 5 without the use of nails or other fastening means and without the use of tools, the invention being useful for constructing vertical walls, floors, ceilings and the like.

Another object of the invention is that 10 the units form a structure which provides its own arch or bridge in floors as well as walls and when used in walls, will plumb and level themselves to the plane of the foundation without the use of plumbing or 15 leveling instruments.

Another object of the invention is to provide interlocking means between the various units which not only acts to firmly hold the component parts of a structure together, but 20 it also acts to center the stresses and strains so that the greater the strain, the more firmly the units will be pressed together.

A still further object of the invention is to so arrange the units that they will bridge 25 openings formed in the structure without necessitating auxiliary supporting means for that portion of the wall above the opening and by slightly changing the shape of the units around the openings, lintels, jambs and 30 the like can be formed by the units.

A still further object of the invention is to provide the units with transverse and vertical openings which will register with each other when the units are placed in the 35 wall so as to provide air spaces.

This invention also consists in certain other features of construction and in the combination and arrangement of the several parts, to be hereinafter fully described, illustrated in the accompanying drawings and 40 specifically pointed out in the appended claims.

In describing my invention in detail, reference will be had to the accompanying 45 drawings wherein like characters denote like or corresponding parts throughout the several views, and in which:—

Figure 1 is a view of a wall structure constructed from the units.

Figure 2 is a section on line 2—2 of Figure 1.

Figure 3 is a section on line 3—3 of Figure 1.

Figure 4 is a section on line 4—4 of Figure 1. 55

Figure 5 is an end view of one of the units.

Figure 6 is a side view of one of the units, looking toward the bar side.

Figure 7 is an edge view showing the 60 block provided with grooves for sealing material.

Figure 8 is a perspective view of a corner forming unit.

Figure 9 is a perspective view of a female 65 corner forming unit.

Figure 10 is a view of a frame forming unit with its wedges.

Figure 11 is a view showing how one unit 70 at one side of a wall is locked to four units at the other side of a wall.

Figure 12 is a diagrammatic view showing how a floor may be connected with a wall.

Figure 13 is a view similar to Figure 11, but showing the units provided with straight 75 edges.

As shown in these views, the structure is composed of a plurality of units A, each unit comprising a slab part 1, a longitudinally extending keystone shaped bar 2 and 80 the transversely extending keystone bars 3. The bar 2 may be connected with the inner face of the slab 1 by a neck 4 or the said bar 2 may be fastened to the outer parts of the bars 3. The outer faces and edges of the 85 bars 3 taper toward the edges of the unit and the side and bottom walls of the spaces between said bars 3 are beveled inwardly so as to receive the bars 3 of a contacting unit. The edges of the slab and the ends of the 90 bars 3 are beveled, as shown at 5, so that the bar 2 of another unit will interlock with the slab part of the unit on which it is placed, as clearly shown in Figure 4. If desired, the 95 bevel 5 may start a slight distance from the outer face of the slab, as shown in Figure 8, but in this case, portions of the ends of the bars 3 must be left square to accommodate the flat portions of the bars 2. The end of each unit is arranged on an incline from the 100 vertical, as shown at 6.

From the foregoing it will be seen that a

wall constructed of these units will have each face thereof composed of the slabs 1 and the bars 2, there being a row of bars 2 between the upper and lower row of slabs 1, as clearly shown in Figure 1. The beveled edges of the slabs and bars set up an interlocking engagement between the adjacent rows of units and the units of adjacent rows are also firmly locked together by the interlocking bars 3. As shown in Figure 11, each unit of one row is interlocked with four units of adjacent rows. By having the ends of the units inclined, as shown, the units cannot be removed after being put in place unless one starts at the last unit put in place and works backwardly.

It will also be seen that the units are so locked together that they will bridge openings, such as window and door openings formed in the wall, and need no auxiliary supports. It will also be seen that the strains and stresses upon the structure will be centralized due to the keystone bars of one row of units being placed between the beveled edges of the slabs of the two adjacent rows of units, which tends to move all the units inwardly. In fact, the entire unit forms a keystone with small keystones for locking the keystone unit to other units. As shown in Figure 11, the inclined ends of the slabs on one face of the wall are oppositely arranged to those of the slabs on the other side of the wall, thus setting up an interlocking of the parts. The angles on the ends of the units on one side of the wall form keystones in relation to the angles on the ends of the units on opposite side of the wall, thus forming a double flat arch in said wall, causing the interlocked keystones 3 of units on both sides of wall to form a flat arch running lengthwise in said wall. Instead of having the ends of the units inclined, they may be made square or straight, as shown at 6' in Figure 13, but in this case, the small keystones 3' must be arranged on an incline to secure the interlocking effect.

One of the corner forming units is shown at B, this member being the male member and is shown in detail in Figure 8, while the female corner unit is shown at C and in detail in Figure 9. A pair of keystone bars 3' of the male member B is diagonally arranged at the corner unit, while the unit or member C is formed with a pair of diagonally arranged recesses 7 for receiving the keystones 3'. Thus a corner of the structure can be easily provided with these male and female units.

Where a window, door or other opening is to occur in the structure, I use the frame forming units D which are each formed with a frame forming part 8 which is connected with the slab 1' and the keystone bar 2'. A wedge-shaped piece 10 is formed on the outer face of the part 8 at the center thereof so that

a window or door frame can be attached thereto. A wedge member E is used to fill in the space between the complete unit A and the frame forming units D at the sides of the opening, as shown in Figures 1 and 10. 70 These wedges are provided with dovetail or keystone shaped portions for engaging the recesses between the keystone shaped portions of the contacting units.

Figure 4 shows a half unit F used to top off a wall. This same unit can be used to start a wall.

Figure 12 shows how a floor or horizontal part X may be joined to a wall or vertical part X' by a unit G. This unit is made similar to the unit A, but in addition, it is formed on the outer face of its slab part with a half slab 1" and with a half keystone 2" so that these parts will engage portions of an ordinary unit A when this unit is placed horizontally and the unit G is vertically placed. Of course, the half slab in this construction and in the units D and F carry the lateral keystones.

The units may be provided with the longitudinally extending openings 11 and lateral openings 12 may be provided in the units if desired, to furnish vertical and horizontal air passages to ventilate the structure and also, if desired, grooves or channels 13 may be formed in the units so that a sealing preparation may be poured between the units to seal and bind them together. Holes 13' are provided to convey the sealing material to the channels.

These units can be used for building structures of various kinds, and in addition to the ordinary uses, they may be used for building levees, breastworks, emergency buildings and the like. As will be seen, the structure can be added to as desired by simply continuing where left off and adding other rows to increase the height of the structure. The units can also be used for making floors and other horizontal structures, as shown in Figure 12.

As shown in the drawings, some of the units may be formed with one straight end so as to enable the last unit in the course or row to be put in place, the first unit and the last unit having these straight ends. However, if a window or door or other opening intersects the course or row, these straight end units are not necessary.

Special attention is called to the fact that 120 a wall constructed of these units is self-bracing horizontally, vertically and through the thickness of wall and that all stresses and strains are directed by the units to the center of the wall.

It is thought from the foregoing description that the advantages and novel features of my invention will be readily apparent.

I desire it to be understood that I may make changes in the construction and in the 130

combination and arrangement of the several parts, provided that such changes fall within the scope of the appended claims.

What I claim is:—

5. 1. A structure forming unit comprising a slab part, a key part, means on the inner face of the slab part for locking the same to a slab part of another unit, such means comprising keystone shaped projections on the 10 inner face of the slab part.
2. A structure forming unit comprising a slab part, a key part, means on the inner face of the slab part for locking the same to a slab part of another unit, such means comprising keystone shaped projections on the 15 inner face of the slab part, each projection tapering from the key part to the edge of the slab part.
3. A structure forming unit comprising a slab part, transversely arranged keystone forming members on the inner face of the slab part, a keystone bar connected with the central portions of the transverse keystone forming members, the side edges of the 20 slab part being shaped to fit the keystone bar of another unit.
4. A structure forming unit comprising a slab part, transversely arranged keystone forming members on the inner face of the 25 slab part, a keystone bar connected with the central portions of the transverse keystone forming members, the side edges of the slab part being shaped to fit the keystone bar of another unit, and the ends of the unit being 30 arranged on parallel inclines.
5. A structure comprising a plurality of units, each unit consisting of a slab section, transversely arranged keystone bars thereon, a longitudinally extending keystone bar on 35 the transverse bars, the transverse bars of one unit engaging the spaces between the transverse bars of adjacent units, said transverse bars tapering from the longitudinal bar to their outer ends.
40. 6. A structure comprising a plurality of units, each unit consisting of a slab section, transversely arranged keystone bars thereon, a longitudinally extending keystone bar on the transverse bars, the transverse bars of one unit engaging the spaces between the transverse bars of adjacent units, said transverse bars tapering from the longitudinal bar to their outer ends, some of the units having frame forming parts thereon for 45 providing window and other openings.
55. 7. A structure comprising a plurality of units, each unit consisting of a slab section, transversely arranged keystone bars thereon, a longitudinally extending keystone bar on the transverse bars, the transverse bars of one unit engaging the spaces between the transverse bars of adjacent units, said transverse bars tapering from the longitudinal bar to their outer ends, some of the units having frame forming parts thereon and 50 wedge-shaped members for filling the spaces between the regular units and the frame forming units.
8. A structure comprising a plurality of units, each unit consisting of a slab section, 55 transversely arranged keystone bars thereon, a longitudinally extending keystone bar on the transverse bars, the transverse bars of one unit engaging the spaces between the transverse bars of adjacent units, said transverse bars tapering from the longitudinal bar to their outer ends, some of the units being corner ones with the transverse keystone bar at the corner thereof being obliquely arranged and with other corner units 60 having obliquely arranged sockets for receiving these obliquely arranged bars.
9. A structure comprising a plurality of units, each unit consisting of a slab section, 65 transversely arranged keystone bars thereon, a longitudinally extending keystone bar on the transverse bars, the transverse bars of one unit engaging the spaces between the transverse bars of adjacent units, said transverse bars tapering from the longitudinal bar to their outer ends and means on some 70 of the units for connecting a second course of units to the first course.
10. A structure comprising a plurality of units, each unit consisting of a slab section, 75 transversely arranged keystone bars thereon, a longitudinally extending keystone bar on the transverse bars, the transverse bars of one unit engaging the spaces between the transverse bars of adjacent units, said transverse bars tapering from the longitudinal bar to their outer ends and means for permitting sealing material to be placed 80 between the contacting parts of the units.
11. A structure forming unit comprising 85 a slab part, means connected with the inner face of the slab part for locking the same to the slab part of another unit, and a base forming key part on the locking means.

In testimony whereof I affix my signature.

JOSEPH A. BEASLEY.
